PAUL O. UNGER, OF SYRACUSE, NEW YORK, ASSIGNOR TO McMILLAN BOOK COMPANY,
OF SYRACUSE, NEW YORK, A CORPORATION OF NEW YORK.

POST BINDER.

Application filed January 13, 1925. Serial No. 2,104.

This invention pertains to post binders, so called by reason of the fact that one of the two clamping or binding elements to which the cover-boards are hinged is provided with a plurality of upstanding posts or stems to receive and position the notched or perforated sheets of paper, pamphlets, catalogues, or other articles to be bound and held together, the second member being provided with a presser bar or follower similarly notched or perforated to receive the posts, and provided with means for engaging the posts after being pressed firmly down upon the articles bound, which have been previously applied to the posts and rest upon the base-plate or post-carrying member. Means are provided for disengaging the clamps when it is desired to remove, rearrange, replace, or add to the contents of the binder.

The invention is designed to overcome certain defects which have manifested themselves in this very useful type of binder, and primarily the tendency of the locking or clamping elements to loosen their hold upon the posts in handling the binders, particularly when their contents are bulky and proportionately heavy. This undesirable happening is due to the fact that clamps are commonly employed of a type in which each consists of a comparatively thin plate of metal, either notched, or perforated to encircle one or another of the posts, or arranged with one edge bearing against a side thereof, the clamping plates being caused to stand perpendicular to the posts when it is desired to release them, and to be tilted to an angular position for engagement with the posts. Such plates when tilted, present a sharp angular edge to one side, or two such edges to the opposite sides of a post, and such edges tend to bite into the metal posts, and to hold more and more firmly in direct proportion to the increase in force tending to pull upon the clamps in a direction to maintain them in tilted position. It is customary to arrange the several clamps of such binders in like position relatively to the several posts; that is to say, they are generally arranged on the same side of the several posts, and tilt in the same direction, with the result that any tendency of the posts to spring or bend in a direction to free one from its clamp will have a like effect upon all the clamps, and with binders carrying a considerable or heavy body of

sheets, pamphlets, or the like, there is a strong tendency thus to spring or cant the posts and to release them from the clamps.

To remedy this defect I arrange different clamps in opposing relation to each other, or to one another, as two or more than two posts and clamps are employed. By this simple expedient, each clamp opposes any movement of its post in a direction which would tend to free it from an oppositely arranged clamp. Such opposing relation, however, necessitates a novel arrangement of the mechanism by which the clamps are moved to and from the clamping or holding position. It is desirable that this mechanism be simple, strong, and operable by a short and simple manipulation of a single element, as by sliding or turning a knob or button in one or the other direction.

My invention, which is susceptible of somewhat varied embodiment, attains the several objects noted, in a very simple way, well adapted to economical and expeditious quantity production, as will now be pointed out in connection with the accompanying drawings, wherein:

Figure 1 illustrates one embodiment of the invention, in longitudinal vertical section, showing the clamps in substantially perpendicular relation to the posts, or in releasing position;

Fig. 2, a similar sectional view but showing the clamps tilted to cramping or locking position;

Fig. 3, a fragmentary perspective view of the several parts of the clamping or binding elements proper, separated to show their form;

Fig. 4, a perspective view on a small scale, of the post binder containing a supply of sheets or leaves, as in a sheet or order-blank binder, or the like;

Fig. 5, a longitudinal vertical section of the binding elements in a slightly modified form, with the clamps adjusted to release the posts;

Fig. 6, a similar view but with the clamps set to locking position;

Fig. 7, a perspective view of the several parts of the clamping elements proper, separated to show their form and general relation;

Fig. 8, a perspective view on a small scale, of the complete binder with a supply of filler sheets or leaves;

Fig. 9, a longitudinal vertical sectional view of a third form of the binder mechanism, in releasing adjustment;

Fig. 10, a similar view but with the slide 5 moved to the left to cause the clamps to engage the posts;

Fig. 11, a perspective view of the parts of the mechanism separated to show their appearance when removed from the enclosing shell or casing and freed from the restraint exerted thereby upon the several spring elements;

Fig. 12, a perspective view of the two clamp members placed in proximity to show the right and left arrangement of their respective clamping members.

I shall first describe the embodiment of my invention illustrated by Figs. 1 to 4 inclusive. As there shown the binder comprises a base-plate or post support 1, provided with two posts 2 and 3, and a presser bar or follower 4. The base-plate or post support is here represented as a flat bar of iron, steel, or other metal, to which is attached one end of each of the posts 2 and 3. The manner of attachment is unimportant provided it be firm and secure, and permit no play or movement relatively to the base-plate 1. The presser bar or follower 4 is shown of box-like form, or consisting of a base-plate or bar 5 of dimensions preferably the same as those of the post support 1, and a cap or cover section 6 formed of thinner metal, pressed or cut and folded to produce an inverted box or casing to enclose the mechanism by which the follower as a whole is caused to engage the posts 2 and 3 and to be held in close and pressing contact with the leaves, sheets, signatures, pamphlets, catalogues, or other papers to be bound into book form. The cover section 6 may be secured to the plate 5 in any convenient or usual way, but I have shown the ends of the cover section provided with downwardly extended tongues 7, which are passed through openings in the base-plate 5 and clinched or riveted on the lower face thereof, thus affording a good fastening for said cover section 6.

The embodiment of the invention now being described permits application and removal of the presser bar or follower 4 to and from the posts 2 and 3 either laterally or by sliding the follower down lengthwise of or over the posts, thus making possible application of the binder to notched sheets without completely separating the base and following members. This is effected by providing the follower base and cover with notches or open slots 8 extending from the outer edge inward to a depth to permit the follower to be positioned upon the posts to bring its clamps or post-gripping elements into proper engaging relation with the posts under either mode of application of the follower.

The clamping mechanism comprises pivotal or rocking clamps 9 and 10 of the form seen in Figs. 1, 2 and 3, two being shown, one for each post. It is to be understood, however, that any desired number of posts 70 may be employed, and that at least two will, and if desired, any additional number of them may, each have such a clamp associated with it. Each clamp consists of a flat plate 11 of steel or other suitable metal, with one end 12 bent downward at an angle of 45 degrees or thereabouts, and with a downwardly extending leg 13 on each side, reduced at its lower end to form a short tenon 14. These tenons are of a size to enter and seat loosely in openings 15, drilled, punched or otherwise formed in the base-plate 5 as shown in Figs. 1, 2 and 3, and the shoulders at the points where the tenons 14 begin are preferably rounded or beveled to afford a 80 rocking surface, facilitating the tipping of the clamp upon said shoulders as a fulcrum or pivot.

The main plate 11 of each clamp is formed with a slot 16 extending inward from one side edge at a right angle thereto, to a point slightly beyond the mid-width of said plate, the inner end of the slot being here shown as of semicircular form to correspond to the cylindrical form of the post which the slot is to receive. The posts may, however, be of any desired form in cross section, the cylindrical form being commonly used because convenient and economical. The slots 16 are slightly wider than the diameter of the posts 2 and 3, so that when the plates 11 of the clamps stand perpendicular to the posts there shall be no cramping or engagement thereof, but that upon tilting said clamps so as to elevate one wall of the slot and lower the other, the lower edge of one slot wall and the upper edge of the other shall be pressed into firm and engaging contact with the post in said slot.

It will be noted that the two clamps 9 and 10 are alike in construction except for the fact that as they are to be reversed in their relation to the respective posts, they are made right and left, or have the slots opening to opposite edges of the plate 11, if the clamps be viewed with their inclined ends pointing in the same direction. The slots 16 thus extend in like direction or toward the same side of the respective clamps when the latter are placed in reverse position, as above pointed out. On referring to Figs. 1 and 2 it will be seen that clamp 9 is pivoted to the left of the proximate post 2, while clamp 10 is pivoted to the right of post 3, and as both slots 16, when the clamps are in their operative positions, open to the same edge of base-plate 5, said slots will register with the slots 8 of the follower or presser bar 4.

The numeral 17 designates as a whole, a spring element, formed of thin and resilient metal, preferably sheet brass or bronze, and comprising a main horizontal portion 18 of a width to fit with a slight clearance in the top of cover 6, and a downwardly bent end portion constituting a supporting and spacing member 19, the lower end of which rests upon base-plate 5, thus holding the angle of the spring element snugly in that of the cover 6. The main or horizontal body of the spring element 17 is longitudinally slotted to produce a spring tongue 20, which is bent downward so that its free end lies normally or naturally out of plane with the body, as seen in Fig. 3. This tongue 20 is at one side of the mid-width of the body of the spring element 17, to clear the inner end of slots 8 and 16 of the presser bar or follower 4, and the posts which enter said slots, and the forward half of the horizontal body 18 is shortened so that its free end shall not reach into the slots or to the post therein. The inner side of body 18 is carried past said slots and lies against the under face of cover 6, thus affording together with the shortened outer side, adequate support for the spring tongue 20.

To lift the clamps 9 and 10 from their tilted holding position to which they are forced by the free or spring tongue of the spring element 17, to horizontal or post-releasing position, there is provided a slide 21 of the form illustrated in Figs. 1, 2 and 3. This slide is made of suitable metal or alloy, and advisably of such thickness as will permit it to be stamped out or shaped by suitable dies. It is provided with a raised central portion 22 at or about its midlength, to lie against the under face of the cover 6 of the follower, and this raised mid-portion has secured to it a button 23, the shank or stem of which passes through a slot 24 in the cover 6, and is screwed, riveted, or otherwise securely attached to said raised portion 22. Slot 24 permits button 23 to be moved longitudinally within the follower 4, the sections 25 and 26 of slide 21 extending in opposite directions from the raised portion 22 and reaching nearly to the ends of the cover 6.

The section 25 of slide 21 has at a short distance from its extremity a raised rib or bend 27 which, under longitudinal movement of said slide, acts as a cam to ride under and lift the end of the main body or plate 11 of clamp 9 from the position which it occupies in Fig. 2 to that in which it is shown in Fig. 1, the clamp rocking or tilting on the legs 13 as pivotal supports. In thus rising from its inclined to its horizontal position, the main plate 11 of clamp 9 acts in opposition to the tongue 20 of the spring element 17, pressing the same back into plane with the main portion 18 of said

spring element, or practically so. As the camming rib 27 is drawn from beneath the clamp 9, it is tipped to the position shown in Fig. 2 by the downward pressure of the tongue 20 at a point beyond or to the right of the pivotal support. The end of section 25 of slide 21 lying outside of or beyond the rib 27 is provided with a slot 28 to straddle the post 2 and permit longitudinal play or movement of said slide, said slot being furnished with a lateral opening 29 near the rib 27 for entrance and exit of the post. The portion 30 of the side wall of slot 28 which remains after forming the opening 29, rides between the proximate side wall 30 of the cover 6 and the post 2 when the slide 21 is moved in a direction to permit the tilting of the clamp 9 and its cramping action upon the post. It thus bridges and closes that end of slots 8 of the base-plate 5 and cover 6 through which, under different adjustment, the post 2 is introduced or withdrawn.

The section 26 of slide 21 extending from the raised portion 22 in a direction opposite that of section 25, is similarly provided with a longitudinal slot 31 open at its outer end, thereby producing two portions 32 and 33 of unequal length, of which the shorter part 33 corresponds in form and purpose to the bridging member 30 at the opposite end of slide 21, and serves to close the slots 8 through which the post 3 enters and is withdrawn, the slot 31 permitting movement of the slide without encountering the post 3. The longer and wider portion 32 is provided with a V-shaped rib or cam 34, similar to the rib or cam 27 of the opposite branch of slide 21, except that it is of shorter measurement.

As shown in Fig. 1, the cams or ribs 27 and 34, when positioned to elevate or hold horizontal the main plate 11 of clamps 9 and 10, stand under the end of each clamp opposite that which has the downwardly bent tail 12, to which position they are brought by a movement of the slide 21 to the left. When the slide is moved in the right-hand direction, the camming rib 27 moves from under the end of clamp 9 to the right, and entirely clear of the clamp as seen in Fig. 2, but owing to the relatively reversed arrangement of clamp 10, the camming rib 34 beneath it rides from under said clamp to a neutral point where its apex stands beneath the angle formed by the downward bending of the end to produce the tail portion 12. In this position the rib or cam 34 has no influence or effect whatsoever upon the clamp 10, which is hence thrown down to its inclined or gripping position by the spring tongue 20, as is clamp 9 by its spring tongue 20, it being noted at this point that the spring elements 17 are made right and left in the same manner essentially as are the clamps 9 and 10, and for a like reason,

It is believed that the operation of the device is clear from the description already given of the construction and functioning of the parts, and need not be further detailed.

Figures 5 to 8 inclusive illustrate a second embodiment of the invention, which in principle and effect is quite similar to that above described, but in this instance the 10 clamps and the follower are shown with circular openings for the passage of the posts through them; the spring elements are differently constructed; the base and follower members are of tubular form; and the slots 15 extending from the post openings to the edge of the follower are omitted.

Figs. 5 and 6 show the parts assembled and in their releasing and gripping or binding positions respectively. In these figures 20 35 designates the base member and 36 the follower or presser bar, the latter provided with upstanding posts 37 and 38. The manner of making up the base 35 and follower 36 will be apparent upon referring to Fig. 25 7, the construction of the two being essentially the same. A strip or sheet of metal of a length corresponding to the longitudinal measurement of the binding edge of the sheets to be inserted, or slightly longer than 30 such edge, is first folded longitudinally on a line at or near its mid-width, the bend or fold being preferably of semicircular cross section. One free edge is then curled or bent to like form, and finally the other free 35 edge is bent to similarly curved form and pressed into close contact with the first curled edge. This may be conveniently effected by bending the metal sheet about a metallic bar of proper width and thickness 40 and having rounded edges, or in any other well-known manner. This produces a very rigid structure, which though made of relatively thin metal and consequently relatively light, will withstand rough usage without 45 bending or buckling.

The base member 35 is further stiffened and supported against collapse by nipples 39, each internally threaded to receive the threaded lower end of one or another of 50 the posts 37 or 38. These nipples are riveted, spun, swaged, brazed, or welded in place, and thus afford a very firm support for the posts in addition to bracing the base member 35. They also preclude any opening 55 or separation of the tubular body of the base member. In all cases the posts 37 and 38 may, if desired, be formed of separable cylindrical sections, or may be made of oval metal tubing, both being now commonly employed. This is illustrated in Fig. 7 in the 60 respective posts 37 and 38. The base 35 is also provided with tubular hinge lugs 40 at one edge, bent up out of tongues formed by slitting the overlapping edge of the sheet 65 and bending the same into cylindrical form.

These hinge lugs serve to receive pintles or wires 41 by which to attach cover-boards 42 (Fig. 8), the cover-boards being similarly provided with lugs alternating with those of the base 35 and follower 36.

The clamps 43 each consist of a comparatively thin metal plate bent at approximately its midlength to form a gripping section 44 having an opening 45 to encircle and grip the post, and a second 70 section 46 at an angle to the section 44, to be acted upon by suitable means for throwing the gripping section into or out of gripping relation with the posts, and also serving to guide the clamp in its rocking movement. The openings 45 of the clamps when the latter are in position, register with openings 45' in the top and bottom walls of the follower 36. Each clamp 43 is provided at or near its midlength with a transverse 80 slot 47 to receive the upstanding mid-portion 48 of a clamp support consisting of a fulcrum-plate 49 conveniently formed by bending up one end of a metal plate 50 at a right angle to the body of said plate, which latter forms a base for the fulcrum-plate 49, and for a similarly upstanding spacing post or member 51 at the opposite end of base-plate 50, of a width somewhat less than the body of plate 49 and base 50. Thus the base-plate 50 with the upstanding portions 85 49 and 51 constitute a clamp support, fulcrum and guide, and a spacing member between the upper and lower walls of follower 36. The portion 48 of fulcrum-plate 49 is 90 of a height to reach to the upper wall of follower 36, but said fulcrum-plate is cut away at either side of the part 48 to an amount equal to or slightly greater than the thickness of the clamp 43, thus forming two 95 bearing points or fulcras 52 for the plate 49, just beneath the bend in said clamp and in plane with the upstanding portion 48. The upper ends of the fulcras 52 are preferably rounded, but may be V-shaped.

At the meeting line of base-plate 50 and fulcrum plate 49 are formed perforations 53 through which are passed from the inner side, the free ends of a staple-shaped spring member 54, the legs of said spring being 100 passed through said perforations until the connecting end bar of the spring rests directly against the fulcrum-plate 49, after which the legs of the spring are bent upward and carried over the fulcrum-plate 49 and laid 105 into notches 55 between the fulcras 52 and the upstanding mid-portion 48, the legs being left in a substantially horizontal position, with their free ends projecting slightly beyond and on opposite sides of the spacing post 51, and practically flush with the top thereof. They may, however, lie initially above the post and be forced down into the 110 position indicated in Fig. 7, when the base-plate 50 is placed within the follower 36. In 115

that way the springs will be placed under initial tension when the support and spring are placed in the follower. The springs 54 will 5 advisably be formed of round wire of suitable gage, and of a highly resilient metal or alloy, such as steel, spring brass, or phosphor bronze, the latter being preferred. While this mode of forming and positioning the springs is found very satisfactory, I do not 10 means to restrict myself thereto, since any equivalent spring which will serve to lift the actuating end of the clamp may be employed.

Each clamp-supporting plate is anchored 15 or secured in place in any usual or convenient manner. A simple way of accomplishing this result is to place the base-plate 50 upon a suitable anvil or support, and to lay the follower 36 with the inner face of its bottom upon the plate 50, both inverted, and with a well tempered cone-pointed punch form indentations in the exposed face of the follower, which will cause corresponding projections on the opposite face and indentations in the under side of base-plate 50, filled 20 by the projections forced out on the proximate face of the follower. This, however, is suggestive only.

For positioning the clamps 43 to release the posts 37 and 38, there is provided a slide 30 56, which may conveniently be formed of a thin flat strip of suitable metal or alloy, such as steel, phosphor bronze, or the like. At its midlength this slide has a raised portion, as shown in Figs. 5, 6 and 7, of a height to contact with the under face of the top wall of follower 36 when the remaining portions of the slide lie flat upon the bottom wall thereof. Said slide 56 is bifurcated at its ends, 35 the space between the two forks at each end being such as to cause said forks to pass on opposite sides of but close to the base 50 of the clamp support, which thus serves as a guide for the slide. The forks at one end of slide 56 are provided with cams 57 of approximately inverted V form, which may be readily and cheaply produced by bending the ends of said forks into the form shown 40 in Fig. 7. Similar but slightly differently shaped cams 58 are in like manner formed near the extremities of the forks at the other end of slide 56. The main body of slide 56 rests upon the floor of the interior space of follower 36, as seen in Figs. 5 and 6, and slides thereon, movement being imparted to the slide by a button 59 located just above the top wall of the follower, and connected with the raised portion of slide 56 by a shank or stem passing through a longitudinal slot 60 in the top wall of said follower and secured to the raised portion of said slide in any convenient manner.

The parts being constructed as above described, are assembled in the relative positions illustrated in Fig. 5, which shows the

clamps in their post-releasing position, the cams 57 and 58 standing beneath the post-encircling sections of said clamps. The actuating sections of the clamps 43 are shown in inclined position, the post-receiving sections of the clamps being pointed in reverse directions. This is important because of the bracing effect produced when either post 37 or 38 is subjected to stress tending to swing it to clamp-releasing position. Obviously, any force tending to release one clamp 43 by such shifting or springing of the post will be effectively resisted by the other clamp, which will be made to bind proportionately more tightly. Whether the gripping ends of the actuating ends of cams 57 and 58 be turned toward the extremities of follower 36 is immaterial so far as concerns this mutually compensating action of the clamps, but a slightly different positioning of said cams might be necessary in order to bring them to the most advantageous positions for alternately lifting the clamps and moving out of lifting position.

The operation of the device will be apparent, and as in the first described form requires merely the sliding of the button 59 the length of the slot in which its shank plays, with consequent movement of the slide itself.

Figs. 9, 10, 11 and 12 illustrate another and slightly variant embodiment having, however, in common with the two forms already described, the material features of the invention, to wit: A base member of post-support provided with posts; a follower; post-engaging clamps carried by said follower and set in opposed relation; and a single slide fashioned to act simultaneously upon the several clamps and to cause or permit their movement into and out of post-gripping position, according to the direction in which the slide is moved.

Referring to Figs. 9 to 12 inclusive, 61 designates a supporting base-plate or bar provided with upstanding posts 62 and 63, which may be integral or sectional and of any suitable cross section, and 64 designates the follower within which are contained the clamps and actuating slide. The clamps are of the same design and fulcrumed in the same manner as in the construction shown in Figs. 1 to 3, inclusive, but the slide is in the present instance placed above instead of below the clamps, and the spring elements as well as the cams are formed integral with the slide. So, too, instead of showing the actuating button made fast to the slide, it is here shown as rotatable about a fixed axis and provided with an eccentrically placed pin movable in a transverse slot in the slide, to effect its reciprocation. Except as thus indicated, the follower 64 may be the same as in the embodiment of the invention shown in Figs. 5 to 8 inclusive.

The form of the slide when relieved of the restraint incident to its placement within the follower shell and between the upper wall thereof and the clamps, will be apparent upon reference to Fig. 11, in which 5 65 designates the slide provided at or near its midlength with a longitudinal slot 66 through which passes the shank or stem 67 of a turnbutton 68, said slot 66 having also 10 a lateral extension 69 to receive an eccentrically placed stud or pin 70 projecting downwardly from the under face of the button 68. The stem 67 passes through openings in the upper and lower walls of 15 follower 64, and has its lower end headed, riveted, or otherwise secured against pulling out of its seat in the lower wall of the follower, as seen in Figs. 9 and 10. The upper and lower walls of follower 64 have at or 20 about their midlength, circular openings 71 for the passage of stem 67, and the upper wall has also a curved slot 72 to permit the movement of stud or pin 70 in a circular path. As seen in Fig. 11, the follower 64 25 is provided with slots 73 opening to its outer longitudinal edge, to permit application and removal of said follower to and from the posts 62 and 63 either longitudinally or laterally of said posts.

Slide 65 is provided with slot-closing tongues 74 and 75, similar to those of the second construction described. Separated from the free end of tongue 74 a distance sufficient to permit entrance or exit of post 30 62 whenever tongues 74 and 75 are sufficiently withdrawn to clear the slots 73, is a spring finger 76 which, being curved upward slightly out of plane with the body of slide 65, bears against the under face of 35 the top wall of follower 64, and tends to press down that end of the slide of which it forms part. Lying next to and inwardly from the finger 76 is a substantially V-shaped cam 77, integral with slide 65, and 40 formed by slitting said slide longitudinally from about the free end of finger 76 to the base thereof, and bending the portion lying between said finger and the medial longitudinal line of slide 65, first downward 45 and then upward, to the shape shown in Figs. 9, 10 and 11. Still further inward from cam 77 the slide 65 is again slit to produce a long spring 78, the base of which is coincident, or practically so, with the 50 bases of finger 76 and cam 77, this spring 78 being bent downward at its free end.

As seen in Fig. 11, the outer longitudinal edge of spring 78, that is to say, the edge 55 lying toward the slotted edge of follower 64, is located sufficiently inward to permit reciprocation of slide 65 without said spring finger colliding with post 62. At its opposite end slide 65 has in addition to the slot-closing tongue 75, two downwardly bent 60 members 79 and 80, of which 79 acts as a

clamp-lifting cam, and 80 as a clamp-tilting or depressing spring. These elements 79 and 80 are, like those already described, integral with slide 65, and are produced by longitudinally slitting said slide along a common line, and severing the strip so produced at or about its midlength, thereafter bending down the two portions, one to form the cam 79 and the other to form the spring 80.

The clamps 81 and 82 are shown in the several figures, but on a somewhat larger scale and in perspective, in Fig. 12. As in the first embodiment, they comprise each a flat metal strip bent to form a main body 80 portion 83 and tail or actuating portion 84, the body portion of each clamp being provided with an open-ended slot 85 extending inward from one longitudinal edge of the clamp toward the opposite longitudinal edge. The opposite sides of each clamp are provided with supporting legs 86, each with a short tenon 87 to enter seats 88 in the lower wall of the follower shell.

The parts being thus fashioned are assembled within the shell of follower 64 in the relation illustrated in Figs. 9 and 10, Fig. 9 showing the clamps in their post-releasing adjustment, to which they are brought through a right-hand longitudinal movement of slide 65. Under such adjustment the springs 78 and 80 lying over the tops of the clamps are brought into and held in plane with the body of slide 65, and cam 77 will lie above and hold in its depressed position the actuating end 84 of clamp 81, while cam 79 having ridden beneath and lifted the free end of the notched body of clamp 82, will hold it in horizontal or post-releasing position. Conversely, if slide 65 100 be moved longitudinally to the left, as the parts appear in Fig. 9, cams 77 and 79 will ride clear of the clamps, and permit springs 78 and 80 bearing upon the upper faces of the notched portions at a point well in advance of the fulcrum 87, to tip the notched section of each clamp downward at an angle to the post passing through the notch. In this way the clamps are caused to grip the posts firmly, and said clamps being fulcrumed one to the right and the other to the left of the respective posts, will act in opposition one to the other and prevent the posts from springing or swaying in either direction, thereby precluding release of the 110 clamps through either post assuming a position other than its normal position perpendicular to the supporting base.

While the description here given sets forth construction which operate very satisfactorily, I do not mean to restrict my claims specifically thereto, it being apparent that details may be modified, that the clamps may be differently fulcrumed or pivoted, that the slides may be moved by different 120

means, and so as to other matters. The essential features are: The arrangement of the clamps in relatively opposed relation, and their simultaneous operation through a single slide acting upon two or more clamps thus relatively opposed.

Those portions of the clamps which engage the posts, and if desired the clamps as a whole, will advisably be tempered or hardened, to enable them to maintain sharp engaging edges or angles and to resist wear, and the spring elements throughout will similarly be tempered or made resilient by proper heat treatment, hammering, rolling, or such other usual treatment as is suited to the particular metal employed.

At least two posts are necessary to carrying out the invention above set forth, but the number may be increased as desired, and clamps may be applied to two posts, or to more than two, but at least two of the clamps should be in opposed relation, one fulcrumed to the left of its associated post and the other fulcrumed to the right of its associated post, so that they shall act to prevent swaying or springing of the posts in either direction. As the several posts are connected both by the follower and by the interposed sheets, pamphlets or articles bound, it is manifest that if two posts be so held and prevented from swaying, the others will necessarily maintain their perpendicular position, but greater resistance will be afforded by providing each of a larger number of posts with clamps, and arranging one half to brace against left-hand movement and the other half to brace against right-hand movement. Since more than two posts cannot be employed without using at least two, and as the bracing effect is afforded in the use of two with the clamps

in reversed position, two are mentioned in some of the claims for clearness of definition, but recital of two is not intended to exclude employment of more than two. 45

What is claimed is:—

1. In a post binder, the combination of a base plate provided with at least two posts; a follower having openings to receive said posts; pivotal clamps carried by said follower, one for each post, each clamps having its pivot on a side of the post opposite to that on which the pivot of the other clamp is located; and a single longitudinally movable slide carried by the follower and having cam portions to act upon the pivoted clamps to move their post-gripping portions from gripping into non-gripping position when the slide is moved in one direction, said slide being further provided with 50 spring members which act to restore the clamps to gripping position when the slide is moved in the reverse direction. 55

2. In a post binder, the combination of a base-plate provided with a plurality of 60 posts; a follower having slots to receive said posts, said slots extending to the outer longitudinal edge of the follower; clamps carried by said follower, one for each post; and a single longitudinally movable slide 65 provided with springs which serve when the slide is moved in one direction to throw the clamps to post-gripping position, and further provided with cams and with slot-closing tongues, said cams serving to move 70 the clamps to post-releasing position and withdraw the tongues from slot-closing position, when the slide is moved in the reverse 75 direction.

In testimony whereof I have signed my 80 name to this specification.

PAUL O. UNGER.
